UNITED STATES PATENT OFFICE.

GEORGE W. WEBB, OF KANSAS CITY, MISSOURI.

BAND OR STRAP.

1,182,064.

Specification of Letters Patent.

Patented May 9, 1916.

Application filed March 8, 1915. Serial No. 12,953.

To all whom it may concern:

Be it known that I, GEORGE W. WEBB, a citizen of the United States, residing at Kansas City, in the county of Jackson and State of Missouri, have invented certain new and useful Improvements in Bands or Straps; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to a band or strap, and more particularly to a band or strap comprising a plurality of plies of heavy canvas, or the like, and especially adapted for use as a driving belt, harness or other article subject to severe tensile strain; the principal object of the invention being to provide a band or strap with means for maintaining the original width and thereby prevent longitudinal stretching under the tensile strain. In accomplishing this object I have provided a stiffening rib which may be applied to the band or strap while the latter is under construction, and is adapted when properly installed at proper intervals throughout the length thereof to not only hold the ply body extended transversely to maintain the width of the body under longitudinal strain, but also to hold the plies of the body together; a preferred form of rib and combination thereof with a ply body being illustrated in the accompanying drawings, wherein:

Figure I is a perspective view of a portion of a band or strap constructed according to my invention. Fig. II is a cross section of the same, giving an edge view of one of the ribs. Fig. III is an enlarged detail perspective of one of the ribs.

Referring more in detail to the drawings: 1 designates a portion of a band, strap or other ply body comprising a plurality of plies of heavy canvas; the material of which the body is composed and the specific construction of the body, however, being immaterial, as my improvements are not necessarily limited to the details of structure herin illustrated.

Applied to the body 1, preferably by embedding the same between the plies thereof, is a rib 2, which may be formed from a

single piece of sheet metal of such length that when it is in position between the plies of the body its ends will lie adjacent the side edges of the body. The material of which the rib is formed is preferably such that the teeth 3 may be stamped from the body portion and projected through the plies of the body and the ends of the teeth clenched into the opposite faces of the body to fasten the plies together, hold the rib in place and maintain the width of the body when longitudinal tension incident to ordinary use thereof as a belt, harness, strap or the like tends to draw the material toward the center and thereby diminish the original width of the band or strap. In forming the rib as suggested above, the teeth 3 may be stamped from opposite edges of the body portion 2 at intervals throughout its length and bent up at right angles to the body.

In assembling the ply body a number of ribs are located at intervals throughout the length of the body, preferably by embedding the same between the plies thereof and with the teeth 3 projected through the plies that lie on opposite sides of the rib, so that the ends of the teeth extend from opposite faces of the body and may be bent over and clenched into the opposite faces of the body to fasten the plies together and firmly anchor the ribs in place; the ends of the teeth on each rib being preferably bent in opposite directions forming a point intermediate the ends of the rib to form a more rigid shoulder for holding the material against contraction under longitudinal or tensile strain.

It is apparent that when a band or strap is provided with a sufficient number of ribs and is used in the ordinary manner, the ribs will hold the band or strap against contraction under longitudinal strain incident to the usual use of the band or strap as a driving belt, harness, or the like, and thereby prevent longitudinal stretching of the body.

Having thus described my invention, what I claim as new therein and desire to secure by Letters-Patent, is:

1. A band or strap comprising a plurality of plies of flexible material and spaced ribs of a relative rigid material extending transversely between the plies and having means for attaching the plies together and the ribs in place.

2. A band or strap comprising a plurality of plies of flexible material, and a relatively rigid rib located between the plies transversely thereof, and having fastening members for anchoring the rib in place and connecting the several plies.
3. A band or strap comprising a plurality of plies of flexible material, and a relatively rigid rib applied transversely of and fastened between the plies.
4. A band or strap comprising a flexible strip and a relatively rigid rib applied transversely to the strip and having teeth struck therefrom at intervals throughout its length and penetrating the strip at intervals throughout the width thereof to form a stiffening rib.
5. A band or strap comprising a flexible strip and relatively rigid rib applied transversely to the strip and having teeth struck therefrom at intervals throughout the length thereof and penetrating the strip.

with the teeth at opposite sides of a point intermediate the ends of the rib bent in opposite directions to clamp the rib to the strip and lock the same thereto. 25

6. A band or strap comprising a plurality of plies of flexible material and a relatively rigid rib located between the plies and having a plurality of teeth struck from the body of the strip at intervals throughout its length and projected from opposite sides of the rib, with the teeth penetrating the plies and folded over the outer surfaces thereof at intervals throughout the width of the band or strap to stiffen the same transversely and connect the plies. 30 35

In testimony whereof I affix my signature in presence of two witnesses.

GEORGE W. WEBB.
